Attorney.

UNITED STATES PATENT OFFICE.

JAMES A. ENSLEY, OF COVINGTON, KENTUCKY, ASSIGNOR OF ONE-THIRD
TO JOHN B. SIMON, OF NEWPORT, KENTUCKY.

NUT-LOCK.

SPECIFICATION forming part of Letters Patent No. 561,776, dated June 9, 1896.

Application filed December 7, 1895. Serial No. 571,365. (No model.)

To all whom it may concern:

Be it known that I, JAMES A. ENSLEY, a citizen of the United States, and a resident of the city of Covington, in the county of Kenton 5 and State of Kentucky, have invented certain new and useful Improvements in Nut-Locks, of which the following is a specification.

The several features of my invention and the various advantages resulting from their 10 use, conjointly or otherwise, will be apparent from the following description and claims.

In the accompanying drawings, making a part of this application, and in which similar letters of reference indicate corresponding 15 parts, Figure 1 is a view in perspective of a bolt and nut and locking-key constructed according to my invention. Fig. 2 is a view in perspective of the locking-key, shown on an enlarged scale. Fig. 3 is an end view of the 20 nut. Fig. 4 is an elevation of the bolt and a vertical central section of the nut and an edge view of the key, these parts being locked together and showing a mode of applying the key to the bolt. Fig. 5 is an elevation of the 25 bolt and a vertical central section of the nut and elevation of the key and illustrating a mode of using the key when the end of the bolt remains in the nut when the latter is in place. Figs. 3, 4, and 5 are on the same scale 30 as Fig. 1. Fig. 6 is a view in perspective of a nut and a punch constructed by me to form the nut according to my invention. Fig. 7 is an elevation of the end portion H of the bolt.

I will now proceed to describe my invention 35 in detail.

A indicates the bolt. This bolt may vary in size and shape, and the head portion B 40 may be of any desired configuration. That end II of the bolt which is opposite to the head is screw-threaded. This screw-thread C may be of any desired pitch and size. A nut D is provided and therein is formed a screw-thread E of a kind suitable to engage the screw-thread on the bolt. The shape of 45 the nut D may be varied at will, and where a monkey-wrench or similar form of wrench is to be employed and applied to the edges of the nut to turn the latter the latter will have a requisite number of flat sides, as F, on what 50 would otherwise be denominated the "periphery" of the nut.

To apply my invention, I provide a groove G across the end H of the bolt. This groove may be formed by raised flanges or ridges, but is preferably formed by cutting into the 55 metal of the end of the bolt, as shown. Such a mode is more advantageous, as it economizes metal and is more readily and cheaply carried into effect. In the nut I form a receptacle for the key K. In application one 60 end of the key is held by the nut screwed onto the bolt, and the key is then bent or moved into the groove in the end H of the bolt.

A novel and advantageous mode of holding the key consists as follows: I form in the nut 65 a groove M, interrupting the screw-thread of the nut at the point where the screw-thread is present, the groove being parallel, or substantially so, to the axis of the screw-hole of the nut, and to prevent the key from slipping 70 forward I provide it with a head K². A cheap and convenient mode of forming this head consists in bending up one end of the straight piece which is to form the key. The key-piece preferably fills the groove M to or nearly 75 to the plane where the threads of the bolt would come.

Where the key K with head K² is employed and it is desired the head shall not project beyond that side of the nut which is toward 80 the head of the bolt, I provide a recess M² in the nut at the end of the groove M, as shown, for the reception of said head of the bolt. If this recess were not present and the head K² were present outside of the nut D and between the latter and the head of the bolt, the 85 head would take up valuable room and abbreviate the valuable working portion of the bolt.

In applying my perfected invention in its 90 most advantageous form I proceed as follows: The bolt is applied to connect those parts of the splice, union, structure, or mechanism for which it is designed or utilized. The key K is then placed in position in the groove M 95 of the nut and its head K² is located in the recess M². The nut is now screwed onto the bolt and screwed home, thereby performing its functions of holding together the parts it was designed to connect. The key K, except its head, is thus far straight, and it is 100 of some non-elastic material, the preferred

material being a non-elastic metal capable of being readily bent. That part of the key projecting beyond the end H of the bolt is now bent down into the adjacent groove G of the bolt, substantially as shown in the drawings. Where the end H of the bolt projects beyond the adjacent face of the nut, the free end of the key is preferably bent around the end of the bolt, as shown in Fig. 1; but in other cases the preferred length of the key beyond the nut does not exceed the diameter of the bolt. Then the key can be readily bent into the groove G of the bolt whether the faces of the end of the free end H of the bolt and the back side P of the nut are in the same plane (seen in Fig. 4) or the end of the bolt is within the nut, (see Fig. 5,) the bolt in the latter case being somewhat short.

The bolt can be unlocked by human agency properly and intelligently applied to unlock it, but will be thoroughly locked and the nut will not unscrew through vibrations of the parts nor by force (within reasonable limits) brought to bear against or in connection with the faces or periphery of the nut.

It will be observed that the construction of my locking device in connection with the bolt and nut is simple. My device is obviously cheap and economical of construction and of material. The invention is easily applied and effective in function and advantageous in results.

As before indicated, my invention is applicable to the nut and bolt whether the end of the bolt projects beyond the face P of the nut or is flush therewith, and, being short of length, remains within the nut.

When desired, more than one transverse groove G may be present in the end of the bolt. Such increase in the number of grooves will rarely be necessary, except in cases where great nicety of adjustment of the coupling union is required.

Fig. 6 illustrates a means and mode of forming the groove M and recess M². R indicates the punch, having a shank R² of size to form the screw-hole of the nut. At one side of the shank and longitudinal therewith is a fin or raised portion R³, and farther back on the portion R³ is another fin R⁴, whose outer edge or back extends still farther out from the axis of the punch than does the back of portion R³. When the punch is made to operate on the blank which is to form the nut, the shank R² punches out the main hole and the raised portion R³ punches out the groove M and the fin R⁴ makes the recess M², the punch stopping after the fin R⁴ has advanced far enough into the iron of the nut-blank to form said recess M². Fig. 6 shows the nut as having been already operated upon by the punch. This operation indicates the simplicity of the operation whereby the groove M and recess M² are formed simultaneously with the screw-hole of the nut.

What I claim as new and of my invention, and desire to secure by Letters Patent, is—

1. In a nut-lock, the combination of the bolt having the end transverse groove, and a nut having the groove M, and the recess M² at the end of the groove, and the key having the head adapted to fit the recess M², while the key fits into the groove, and is bent so as to interfit the groove of the bolt, substantially as and for the purposes specified. 75

2. In a nut-lock, the combination of the bolt having end groove, and a nut having groove M terminating in recess M², and a headed key K, K², whose head fits in the recess M², and a part of its shank lies in groove M, and a portion of its shank is bent down into the bolt-groove, and a remaining portion bent back on the other side of the bolt from where the key lies in groove M, thereby forming an embracing-clasp, substantially as and for the 85 purposes specified. 80

3. In a lock, the combination of a bolt A, having the end portion H screw-threaded with thread C, and having a groove G at, in and across the extremity of the end portion H of the bolt, and a nut D having an interior thread E registering with and engaging the thread C of the bolt, this nut having a transverse groove M extending from the front to the rear of the nut, interrupting the screw-thread of the nut 95 and an enlargement of the groove M in the nut and at the rear of the groove (toward the bolt-head) and a key having a head K², fitting in the said enlargement of the groove M, and extending forward in the groove M, and forward along the bolt, and at the end of the latter extending across the end of the bolt and located in the end groove G thereof, substantially as and for the purposes specified. 90

4. In a nut-lock, the combination of a bolt A having the end portion H screw-threaded with thread C, and having a groove G at, in and across the extremity of the end portion H of the bolt, and a nut D having an interior thread E registering with and engaging the 100 thread C of the bolt, the nut D having a transverse groove M extending from the front to the rear of the nut, interrupting the screw-thread of the nut, and a vertical recess M², in the rear side of the nut and joined to the 105 groove M and extending radially out beyond the groove, and a key K having a head K² at right angles to the axial line of the bolt, and fitted in the recess M² of the nut, a portion of the shank received in groove M, and a portion 110 bent across the threaded end of the bolt and at right angles to the length of the latter and received into the groove G in said end, substantially as and for the purposes specified. 115

JAMES A. ENSLEY.
